UNITED STATES PATENT OFFICE.

WILLIAM BECKER, OF BROOKLYN, NEW YORK.

SNAPPER ATTACHMENT FOR WHIPS.

SPECIFICATION forming part of Letters Patent No. 377,137, dated January 31, 1888.

Application filed November 28, 1887. Serial No. 256,333. (No model.)

To all whom it may concern:

Be it known that I, WILLIAM BECKER, of Brooklyn, county of Kings, and State of New York, have invented a new and Improved 5 Snapper Attachment for Whips, of which the following is a full, clear, and exact description.

This invention relates to snapper attachments for whips, and has for its object to provide a whip-snapper attachment which will 10 form a rigid connection with the whip-tip, and which will be durable.

The invention consists in a whip-snapper attachment constructed as hereinafter described and claimed.

15 Reference is to be had to the accompanying drawings, forming a part of this specification, in which similar figures of reference indicate corresponding parts in all the views.

Figure 1 represents the snapper attachment, 20 partly in vertical section, as applied for use. Fig. 2 is a detail representing a modification in the stiffening-piece for the attachment. Fig. 3 is a horizontal section on the line *x x*, Fig. 1; and Fig. 4 is a detail view showing the 25 stiffening-piece for the attachment.

In the construction of this device I preferably use a quill as a stiffening-piece, owing to its stiffness, it being impervious to moisture, and its natural shape, whereby it is adapted to 30 the tapering form of the whip-tip.

The stiffening-piece 1 is formed of a quill cut off square at one end and preferably cut off diagonally at the other end, and of a sufficient length to extend over the tip 2 of a whip 35 and close up to the loop 3 of the braided or plaited covering 4. The quill, owing to its naturally tapering form, fits over and becomes snugly attached to the tip 4 when slipped onto it, and renders the plaited portion at the neck 40 of the loop 3 stiff, and prevents the loop from becoming limp by wear. A snapper, 5, is shown attached to loop 3. If a quill is not at hand of a natural size to fit tip 2, any-sized quill may be used, as shown in Fig. 2, where 45 the stiffening-piece 1 is formed from a quill slit lengthwise, as at 6, whereby it may yield a little to conform to the size of the tip to

which it is to be applied, and will hold firmly thereto when pushed onto the tip. If the quill be too large for the tip, it can be slit lengthwise and its edges trimmed until, when pressed together, the quill will fit the tip and be held by the plaiting.

The stiffening-piece above described, whether a whole quill or one slit and trimmed, as 50 set forth, is practically a tubular shell or socket-tube. Instead of a quill, I may use a tubular socket-piece of any other material which will answer the purposes of the quill.

The advantage of the quill may be readily 55 seen. It will not rot, it retains its rigidity, is unaffected by moisture, and is sufficiently flexible to adapt it for the purposes of a whip-snapper attachment. By means of this invention a strong and durable whip-snapper attachment is provided.

Having thus described my invention, what I claim as new, and desire to secure by Letters Patent, is—

1. A snapper attachment for whips, consisting of a stiffening-piece formed of a tapering tubular section of a quill, embracing a whip-tip, and a plaited covering extending over the whip tip and strengthening-piece and forming a loop, substantially as shown and described. 75

2. In a snapper attachment for whips, a stiffening-piece consisting of a tapering tubular section of a quill, substantially as described.

3. A snapper attachment for whips, consisting of the combination, with whip-tip 2, of 80 stiffening-piece 1, formed of a section of a quill cut off square at one end and to a point at the other end, and embracing the whip-tip, and a plaited covering, 4, extending over the stiffening-piece and formed with a loop, 3, at the 85 end of the whip-tip, the pointed end of the stiffening-piece extending over the whip-tip and close up to the loop 3, substantially as described.

WILLIAM BECKER.
